RACK CONSTRUCTION

Harry E. Einhorn, Brooklyn, N. Y., assignor to Wilco Metal Products, Inc., New York, N. Y., a corporation of New York

Application June 6, 1955, Serial No. 513,197

4 Claims. (Cl. 211—177)

This invention relates to rack constructions, and is particularly directed to improvements over the invention disclosed in my prior copending patent application Serial Number 502,493, filed April 19, 1955, now Patent No. 2,815,862, granted December 10, 1957.

While the present invention has been primarily developed and employed in connection with a rack for supporting shoes in convenient position, and will be described hereinafter with particular reference thereto, it is appreciated that the instant rack construction is capable of wide application, and all such uses are intended to be comprehended herein. The particular embodiment of the present invention, which is illustrated in the drawings and which will be described hereinafter in greater detail, comprises generally a pair of laterally spaced side members having their lower ends adapted for engagement with a supporting surface, and at least two laterally extending elements connected between the side members to define therewith a frame structure. The laterally extending elements may be provided with suitable means for supporting shoes, or the like, as desired.

As is well known to those versed in the art, racks of the type described, say for supporting shoes, or the like, have heretofore been fabricated of relatively expensive, seamless tubing, and fixedly secured together in their erected or assembled condition. That is, the side members were necessarily bent of tube stock, and the lateral elements either welded, swaged or bolted to the side members. This, of course, involved time-consuming and laborious assembly operations; and, the finished articles required considerable space in shipment and storage, all adding to the ultimate sale price.

Further, in the particular rack construction disclosed in the above-mentioned copending patent application, at least one of the laterally extending elements precisely formed compound bends. In addition to the manufacturing difficulties inherent in such construction, the compound bends prevented the bent elements from lying flat, in one plane, and thus presented storage and packing problems.

It is, therefore, a general object of the present invention to provide a rack construction of the type described, which overcomes the above-mentioned difficulties, and which is well adapted for quick and easy assembly and disassembly by persons of only ordinary skill, all without the use of any tools.

It is a more particular object of the present invention to provide a rack construction having the advantageous characteristics mentioned in the foregoing paragraph, wherein the component parts in their disassembled condition may be collapsed to define a relatively flat package of minimum size. More specifically, each of the component parts of the instant device may be substantially coplanar in configuration, and thus readily superposed one above the other for convenience in packaging and economy of space.

It is another object of the present invention to provide

2

a rack construction having the advantageous characteristics mentioned in the foregoing paragraph, wherein the use of relatively expensive seamless tubing may be completely eliminated, and the side members may be fabricated of relatively inexpensive sheet material, to effect considerable savings in cost, without sacrificing strength, appearance, or ease of manufacture.

It is a further object of the present invention to provide an improved rack structure of the type described, which is staunch and durable in construction and use, requiring a minimum of relatively simple parts, and which can be manufactured and sold at a reasonable cost.

Other objects of the present invention will become apparent upon reading the following specification and referring to the accompanying drawings, which form a material part of this disclosure.

The invention accordingly consists in the features of construction, combinations of elements, and arrangements of parts, which will be exemplified in the construction hereinafter described, and of which the scope will be indicated by the appended claims.

In the drawings:

Fig. 1 is a front elevational view showing a rack constructed in accordance with the present invention.

Fig. 2 is a side elevational view showing the rack of Fig. 1.

Fig. 3 is a sectional view, somewhat enlarged and taken substantially along the line 3—3 of Fig. 2.

Fig. 4 is a partial, bottom plan view of the rack of Figs. 1 and 2.

Referring now more particularly to the drawings, and specifically to Fig. 1 thereof, the embodiment of the invention illustrated therein comprises a pair of upstanding side members, each generally designated 10, and disposed in laterally spaced, facing relation, having their lower ends adapted for engagement with an appropriate supporting surface (not shown). One or more elongate tie or connector members 11 extend laterally between the side members 10, each having its opposite end portions secured to the adjacent side member; and, one or more elongate stay members 12 extend laterally between the side members, spaced from the connector members, and also each having its opposite end portions secured to the adjacent side member.

The side members 10 are preferably identical in construction, one being shown in detail in Figs. 2—4 as of an inverted, generally U-shaped configuration. Further, each of the side members is of tubular construction, being bent of an elongate tube into its U-shaped configuration, and includes an intermediate, generally horizontally disposed bight portion 14 and a pair of parallel spaced, generally vertically depending legs 15, 15. In the assembled condition of Figs. 1 and 2, the free ends 55 of the legs 15 are engageable with an appropriate floor or ground surface for supporting the rack in spaced relation above the latter surface, as will appear in greater detail hereinafter.

In particular, see Figs. 3 and 4, it will be noted that the side members 10 are each formed of sheet stock and rolled or otherwise bent into tubular form. That is, a flat sheet of metal may be rolled so that its opposite side edges are bent into abutting or proximate relation to define a juncture or seam 17 extending longitudinally along and disposed interiorly of the tubular, U-shaped side member.

In order to maintain the edges of the seam or joint 17 in proximate or meeting relation, a pair of spaced straps, generally designated 18, 18 are secured across the joint on the underside of each bight portion 14, and an additional strap, generally designated 19, is secured across the joint on the inner side of each leg 15. It will be noted

that the straps 18, see Figs. 2-4, are each formed with a downwardly bowed medial portion 20 defining an open-ended sleeve extending longitudinally along the respective side member bight portion; and, the marginal side portions 21, 21 define tabs fixedly secured, as by welding or the like to the respective bight portion on opposite sides of the joint 17. A longitudinally central or intermediate region of each downwardly bowed sleeve 20 is cut away or open, as at 22. That is, extending between the opposed tabs 21, 21, and spaced intermediate the ends of the downwardly bowed strap portion 20, is an opening or cutout 22 which divides the sleeve into a pair of spaced, end to end aligned sleeve sections 23. As best seen in Fig. 3, the downwardly bowed sleeve sections 23 are each formed with an internal, longitudinally extending recess 24, preferably facing upwards towards the joint 17. Viewed otherwise, the recesses 24, 24 of each strap 18 define aligned, open-ended grooves or slots, each of which opens through one end of the respective sleeve 20 and into the respective sleeve cutout 22.

Each of the straps 19 is similarly formed with an inwardly bowed medial portion 26 defining an open-ended, vertically disposed sleeve extending longitudinally along the respective side member leg; and, the marginal side portions 27, 27 define tabs fixedly secured, as by welding or the like, to the respective leg on opposite sides of the joint 17.

While the illustrated embodiment discloses two straps or sleeves secured to the bight portion of each side member, and a single strap or sleeve secured to the inner side of each leg, it is appreciated that different numbers of sleeves may be employed, if desired.

The connector members 11, 11, two being illustrated in the drawings, are preferably disposed in generally parallel spaced relation, and extend laterally in substantially the same horizontal plane, between the bight portions of the side members. As the connector members are preferably identical, a description of one will suffice.

Each connector member 11 is preferably fabricated of rod stock, and includes an elongate, substantially straight central or intermediate portion 29 which extends horizontally between and in a plane slightly below the side member bight portions. The connector members or rods 11 are each bent transversely, in a horizontal plane, at spaced points 30 (only one being shown in the drawing) to define parallel spaced, inner connector member end portions 31, each of which is further bent, as at 32, substantially 180° in a horizontal plane, to define a pair of terminal extensions or outer connector end portions 33 disposed in substantial parallelism with each other and with the inner connector end portions 31. As best seen in Fig. 4, each inner connector end portion 31, its adjacent outer connector end portion 33, and the connecting bend 32 combine to define a generally U-shaped, transversely disposed connector section.

Each outer connector end portion or terminal extension 33 is formed on its inner side with a lateral protuberance, lug or stud 34 projecting toward the inner connector end portion 31. The protuberance 34 may be formed by swaging or otherwise, as desired. As best seen in Fig. 3, the outer connector end portions or terminal extensions 33 are each of circular cross-section and of a size adapted for insertion into one of the sleeves 20; and, the protuberance 34 of each terminal extension is proportioned so as to pass through the respective groove 24 upon insertion of the associated terminal extension. Further, the protuberances 34 are each arranged to permit insertion and withdrawal of the respective terminal extension 33 only when the associated connector member is in a predetermined angular relation with respect to the sleeve 20 and the associated side member. The protuberance 34 is also arranged on the terminal extension 33 so as to pass entirely through one of the grooves 24 and into the adjacent sleeve cut-out or opening 22 upon insertion of the respective terminal exten-

sion. As the terminal extension 33 is of circular cross-section, reception of the protuberance 34 in the opening 22 enables the terminal extension to be rotated in the sleeve 20, to change the relative angularity of the connector member and frame side member. This will displace the protuberance 34 out of alignment with the groove 24 so that the protuberance is engageable with a bounding edge of the cutout 22 to prevent withdrawal of the terminal extension from the sleeve 20.

It will now be appreciated that each connector member 11 is substantially coplanar, having its central portion 29, and inner and outer end portions 31 and 33 all disposed in substantially the same plane; and, as the protuberance 34 projects from the outer or terminal extension 33 toward the inner connector member end portion 31, it will be seen that the connector member must be disposed substantially coplanar with respect to each frame side member 10 to permit insertion and withdrawal of the terminal extensions in the side member sleeves 20. However, as the operative position of Fig. 1 illustrates, the frame side members 10 are disposed substantially normal to the plane of the connector member 11 when in use, so that inadvertent or accidental removal of the terminal extensions 33 from their respective sleeves, and separation of the connector member from the frame side members is effectively prevented. That is, the grooves or slots 24 each combine with their adjacent sleeve cutout 22 to define a bayonet type opening for receiving the protuberance 34 in one angular position of the terminal extension 33 and retaining the latter in the sleeve when the terminal extension is rotated out of the particular angular disposition.

The connector terminal extensions 33 may, if desired, be integrally connected directly to the central connector member portion 29, to eliminate the inner connector member end portions 31, without substantially altering the manner of insertion and withdrawal described above. However, the illustrated connector member construction is preferred as the inner end portions 31 and bends 32 afford the connector members a degree of longitudinal resilience or extensibility, which eliminates the need for precisely locating the straps 18.

It will also be appreciated that each of the straps 18 may be constructed with only one of the sleeve sections 23, the other being eliminated, without changing the bayonet-type connection with the connector member terminal extension. Hence, the sleeve 20 may consist of only one sleeve section 23 having its opposite ends open, so that the term "sleeve" as used in the claims may refer to a single sleeve section.

The stay members 12, also shown for purposes of illustration as two in number, are identical to each other and preferably fabricated of rod stock. Each of the stay members 12 includes an elongate, central or intermediate straight portion 37 and angulated terminal portions or extensions 38 at its opposite ends. More particularly, the angulated portions 38 are bent at right angles to the intermediate portion 37, so as to depend generally vertically therefrom for reception in respective sleeves 26. Each of the stay members 12 thus extends generally horizontally between an opposed pair of respective side members, and has its end portions 38, 38 slidably insertable into and withdrawable from respective sleeves 26, 26 of the spaced side members. In this manner, the tie members 11 and stay members 12 serve to connect and maintain the side members 10 in upstanding relation, combining with the latter to define a relatively rigid, self-standing structure.

When the self-standing structure is intended for supporting shoes and the like, upstanding corrugated wires 39 and 40 may be fixedly secured, respectively, to the intermediate portions of the tie members 11 and stay members 12.

As the tie or connector member terminal extensions 33, and stay member terminal extensions 38 are slid-

ably insertible into and withdrawable from their respective sleeves 20 and 26, it will be apparent that the rack construction may be quickly and easily assembled, as by insertion of the terminal extensions, and disassembled by withdrawal of the latter. The stay member terminal extensions 38, 38 are disposed in substantial parallelism, so that the stay members are substantially coplanar in configuration, as are the connector members 11 and side members 10, as noted hereinbefore. Therefore, in disassembled condition, the various parts of the rack are all relatively flat and may be horizontally superposed or laid one upon the other to form a relatively flat package occupying a minimum of space.

From the foregoing, it is seen that the present invention provides a rack of staunch and sturdy construction, which may be readily assembled and disassembled without the use of any tools, which otherwise fully accomplishes its intended objects, and which is well adapted to meet practical conditions of manufacture and use.

Although the present invention has been described in some detail by way of illustration and example for purposes of clarity of understanding, it is understood that certain changes and modifications may be made within the spirit of the invention and scope of the appended claims.

Having thus described my invention, what I claim as new and desire to secure by Letters Patent, is:

1. In a rack construction, a pair of inverted generally U-shaped side members disposed in laterally spaced, facing relation and adapted to rest in upstanding condition on a supporting surface, a pair of generally horizontally disposed open-ended sleeves each extending longitudinally along and fixedly secured to the underside of the bight portion of a respective one of said side members, said sleeves each being formed with a longitudinal internal groove opening through opposite sleeve ends, an elongate connector member extending between a sleeve on one side member and a corresponding sleeve on the other side member, said connector member having transversely angulated end portions each removably inserted into the adjacent one of said sleeves, a lateral protuberance on each of said connector end portions shaped for movement through and beyond the groove of the respective sleeve upon insertion of said connector end portions in said sleeves, said protuberances each being disposed for abutting engagement with an edge of the respec-

tive sleeve when said side members are in said upstanding condition to prevent withdrawal of said connector end portions from said sleeves, and a stay member extending laterally between and having its opposite ends each connected to a leg of said opposed side members, to prevent movement of said side members out of said upstanding condition and retain said connector end portions in said sleeves.

2. A rack construction according to claim 1, in combination with a pair of additional sleeves extending longitudinally along and fixedly secured to the legs of respective side members, and transverse extensions on opposite ends of said stay member removably inserted into said additional sleeve.

3. A rack construction according to claim 1, wherein each of U-shaped side members is fabricated of initially flat stock rolled into a tube having proximate edges extending longitudinally of said tube, said sleeves being secured across said proximate edges to hold the latter together.

4. A rack construction according to claim 3, each of said sleeves comprising a strap having opposite marginal portions secured to its associated side member on opposite sides of said proximate edges to hold the latter together, the medial region of each strap between its secured marginal portions being bowed away from the adjacent side member bight portion and combining with the latter to define a passageway for receiving said connector end portions, said grooves being formed in said bowed strap regions for receiving said protuberances upon insertion of said connector end portions, and said bowed strap regions being cut away to receive said protuberances when said side members are disposed in their upstanding condition.
